DENTAL IMPRESSION TRAY

Lucian Graves Coble, Greensboro, N. C.

Application June 11, 1940, Serial No. 339,970

3 Claims.

(Cl. 32—17)

This invention relates to improvements in dental impression trays and, particularly, to a mandibular impression tray for taking an impression of the lower jaw of a patient who has no lower teeth remaining.

In preparing impressions for making dental plates, it is common practice, as is well understood, to press a mass of plastic molding material against and around the gum surfaces and, especially, the ridges of the gum. For thus manipulating this mass of plastic molding material, it is placed in what is commonly referred to as a dental tray so that said material can easily be forced against the surfaces of which an impression is desired. After the impression has been made and the plastic material set, it is necessary to trim and shape the side surfaces of the impression. In most instances, the trays are of metal and, particularly in the case of a mandibular impression tray, it is quite difficult to trim or carve the surfaces of the impression for the purpose of properly shaping the same without interference from the metal constituting the tray in which the impression is retained for purposes of proper support. Due to these difficulties, the principal object of the present invention is to provide a dental impression tray, and particularly a mandibular impression tray, with which an impression can be made with the greatest facility and with which that impression, when set, can be properly supported without interfering with the trimming and shaping operations.

More specifically, the invention contemplates a mandibular impression tray of sectional construction in that it comprises a substantially U-shaped outer member of sufficient width to span the ridges of the patient's gum so as to permit the plastic molding material held in the tray to be pressed against the sides and beyond the ridges, and an inner member loosely supported in the bottom of the outer member so as to become embedded in the plastic material during the making of the impression, this inner member being free to be removed with or as a part of the impression so as to properly support the impression after the latter has been taken out of the outer member of the tray. This inner member of the tray is comparatively narrow so that, when the impression is removed from the outer member and supported only by the inner member, the impression projects an appreciable distance beyond the side edges of the inner member so that the side surfaces of the impression can be trimmed and properly shaped without the implement used for that purpose contacting or engaging against the

comparatively narrow supporting inner member.

With these and other objects in view, the invention consists in certain details of construction and combinations and arrangements of parts, all as will hereinafter be more fully described, and the novel features thereof particularly pointed out in the appended claims.

In the accompanying drawing illustrating the preferred embodiment of the present invention, Figure 1 is a top plan view of the fully assembled tray;

Fig. 2 is a similar view with the inner member removed;

Fig. 3 is a perspective view of the inner member of the tray; and

Fig. 4 is a sectional view on the line 4—4 of Fig. 1.

In the tray as illustrated in the present instance, there is an outer member 10 and an inner member 11, these members being substantially U-shaped so as to correspond in contour to that of the gum of the lower jaw. As is well understood, the tray is dished to accommodate a quantity of moldable plastic material sufficient to have at least a portion of the lower jaw imbedded therein in order that an impression of the whole lower jaw, and particularly the ridges thereof, can be taken. To facilitate handling of the tray, as when forcing it, together with the molding material, against and around the gum, the outer member 10 is provided with a handle 12 which may be rigidly attached to said outer member.

In the present invention, the outer member 10 has one or more recesses or openings 13 adapted to loosely receive a corresponding number of positioning pins 14 on the under face of the inner member 11. This is the only means of attachment between the inner and outer members as it is intended that the inner member shall become embedded in, and practically become a part of, the molded material constituting the impression, and be removed from the outer member 10 along with the impression. In other words, the inner member 11 is loosely held in the outer tray 10, the positioning pins 14 merely preventing lateral or endwise shifting of the two members. To insure the inner member 11 becoming embedded in and adhering to the impression formed by the plastic material, said member may be formed with means for interlocking with the molded material. For instance, a plurality of openings 15 may be formed therein. By reason of the plastic material protruding into these openings

15, the inner member will be securely interlocked with an impression made with the tray.

It will be observed that the inner member is comparatively narrow so that, while an ample quantity of plastic material for the desired impression can be placed in the assembled tray, nevertheless when the impression, together with the inner member, is removed from the tray, after the impression has set, the side portions of the impression will overhang or project beyond the side edges of the inner member an appreciable distance. Thus, the inner member will properly support the impression after the latter has been removed from the tray proper and, at the same time, the reduced width of said inner member permits the side surfaces to be trimmed and shaped without danger of the instrument used in that operation coming into contact with the metal of which the inner member is made. Not only may the inner member be of considerably less width than the finished impression, but it may also be made somewhat shorter without detracting from the support it gives the impression for the purpose of preventing breakage and distortion of the impression during the remainder of the process or handling thereof for properly and accurately finishing it. The use of this readily removable inner member 11, as indicated above, permits the use of an outer member of such dimensions as to carry sufficient molding material necessary to insure obtaining impressions the desired distance, so to speak, upwardly around the sides of the gum surfaces.

Due to the reduced dimensions of this inner member 11, it is deemed preferable to form the same of metal, although other materials which will impart sufficient rigidity to the member may be utilized. The present tray is especially adapted for use in making impressions of patients' gums from which all teeth have been extracted, but it will be understood that, in many instances, it will serve with the same degree of efficiency where there are one or more remaining teeth.

What I claim is:

1. A dental tray comprising a substantially U-shaped outer member having a depression therein of sufficient breadth to span the ridges

of the gum of the lower jaw of a patient whereby a mass of plastic molding material in said depression can be forced against and at least partially beyond the sides of said ridges for making an impression thereof, and an inner substantially rigid U-shaped member loosely received in the bottom of said depression adapted to be embedded in the bottom surface of the plastic material and to be removed from said outer member together with the impression formed by the molded material whereby the latter will be supported by the inner member, said inner member being of less width than the molded material to leave the side surfaces of the impression fully exposed and to facilitate trimming and shaping of the side surfaces of the impression.

2. A dental tray comprising an outer member of sufficient width and depth to span the ridges of the lower gum of a patient and permit a mass of plastic molding material to be forced against the sides of the ridges and beyond the ridges to form an impression thereof, said member having a recess therein, a handle attached to said tray, an inner member loosely supported in said outer member, and a projection on said inner member engaging in said recess, said inner member being removable from the outer member together with said impression to support the latter and said inner member being of less width than the impression to facilitate trimming and shaping the side surfaces of said impression.

3. A mandibular dental tray comprising an outer section having a base and opposite side walls spaced to span the ridges of a patient's gum for forcing a molding material against and beyond the ridges, and an inner section detachably held on the base of the outer section between the side walls, said inner section being of less width than the base and adapted to extend substantially the length of the bottom of a body of molding material used in the tray, and said inner section being removable with the molded material from the outer section to support the mold with the side surfaces of the latter exposed throughout their length whereby they can be trimmed and shaped without contacting said inner section.
